UNITED STATES PATENT OFFICE.

PAUL HAACK AND HEINRICH MUNZERT, OF BERLIN, GERMANY, ASSIGNORS TO THE CORPORATION OF FLINSCHI & CO., OF FRANKFORT-ON-THE-MAIN, GERMANY.

CARBURETER.

No. 890,273.

Specification of Letters Patent.

Patented June 9, 1908.

Application filed December 13, 1907. Serial No. 406,266.

To all whom it may concern:

Be it known that we, PAUL HAACK, merchant, and HEINRICH MUNZERT, engineer, both subjects of the German Emperor, and 5 both residents of Berlin, Germany, (where the post-office address of PAUL HAACK is S. W. 47 Yorkstrasse No. 17, and of HEINRICH MUNZERT O. 17 Koppensstrasse No. 57,) have invented new and useful Improvements in Carbureters, of which the following 10 is a specification.

This invention relates to a carbureter for liquid combustibles, as will be described with reference to the accompanying drawing, 15 which is a longitudinal section through the apparatus.

About the middle of the carbureter, which may be contracted at this part for the purpose of increasing the speed of the current, is 20 situated the nozzle *d* through which the liquid issues, the supply being kept at a constant head by the float *s*. When the suction stroke of the engine occurs the combustible 25 spouts against the pulverizer *z* and forms a cloud a part of which falls back. Combustible also drops from the nozzle.

In order to catch the liquid deflected downwards and that dropping from the nozzle, the lower part *g* of the carbureter contains a distributor *t*, which may be conical or of any other suitable form and may have a corrugated or perforated surface. From 30 this distributor the subdivided liquid drops on to a grating *r'*, the bars of which may be tubes whereinto air enters from without and passes through openings such as *l* into the carbureter, becoming carbureted by the liquid which has fallen on to the tubes. The 35 carbureted air then ascends over the distributor *t* into the middle part of the carbureter where it minglest with the upwardly directed combustible and the aforesaid cloud,

thus forming the mixture for combustion. The upper part *g* of the carbureter may also contain a grating *r*, which may consist of 45 tubes for admission of supplementary air, so as to prevent a large surface to the still nebulous mixture, and is particularly useful for difficultly vaporizable liquids. The suction pipe of the motor is connected with the 50 neck *a*.

Now what we claim and desire to secure by Letters Patent is the following:

1. A carbureter for liquid combustibles comprising a chamber, a nozzle within the 55 said chamber and adapted for issue of the liquid, a pulverizer situated above the said nozzle, a distributor situated below the said nozzle and adapted to receive falling liquid, and perforated tubes, constituting a grating 60 situated below the said distributor and adapted for passage of the air to be carbureted, substantially as described.

2. A carbureter for liquid combustibles comprising a chamber, a nozzle within the 65 said chamber and adapted for issue of the liquid, a pulverizer situated above the said nozzle, a distributor situated below the said nozzle and adapted to receive falling liquid, a 70 grating situated below the said distributor and tubes constituting a grating situated above the said pulverizer and adapted for passage of supplementary air, substantially as described.

In testimony, that we claim the foregoing 75 as our invention, we have signed our names in presence of two witnesses, this twenty-ninth day of November 1907.

PAUL HAACK.
HEINRICH MUNZERT.
